HYDRAULIC DRILL COLLAR RETRIEVING MECHANISM

Franklin L. Le Bus, Sr., Longview, Tex., assignor to The Wash Overshot and Spear Engineers, Incorporated, Longview, Tex., a corporation of Texas

Application January 20, 1954, Serial No. 405,186

8 Claims. (Cl. 166—103)

This invention relates to improvements in drill collar retrieving apparatuses, and more particularly, but not by way of limitation, to improvements in the type of drill collar retrieving apparatuses which simultaneously hold and dislodge stuck drill collars.

As it is well known in the art of drilling, the majority of oil wells drilled at the present time utilize the rotary drilling method. In this method, the drill string consists of a plurality of drill pipe joints secured in tandem relation with a varying number of drill collars depending in tandem relation from the drill pipe and having a drill bit on the lower end thereof. The entire drilling string is secured to a "kelly" at the surface, and in operation, is rotated by a rotary table surrounding the kelly to drill the well bore.

The drill collars are heavy, rigid, tubular members which are difficult to bend. Therefore, when the drill bit is forced from a true vertical course by tilted geological formations or the like and make a crooked bore, the drill collars will rub against the side of the well bore and form an off-set recess commonly called a "key-seat." In a large percentage of oil wells, and particularly deep oil wells, the well bore will contain several of these key-seats. When the drill bit is being removed from such a well bore, the bit will become lodged in one of these key seats, since they are of smaller diameter than the well bore proper. The usual procedure is then to disconnect, and remove from the well bore, all of the drill pipe and a portion of the drill collars; leaving the drill bit and one or more drill collars lodged in the well bore.

The lodged drill collars and bit are usually removed by running a reamer on the end of a string of wash-over pipe down over the drill collars. The reamer reams out the key-seat and frees the drill bit; whereupon the drill bit and attached collars fall to the bottom of the well bore. It is then necessary to run another set of tools into the well bore and remove the drill bit and collars, which are usually damaged from the previous fall.

The present invention contemplates a novel drill collar retrieving apparatus adapted to recover the lodged drill bit and collars in one trip of tools in the well bore without damaging the drill bit or collars. The retrieving apparatus is carried in the wash-over string and engages the uppermost drill collar as the wash-over pipe is initially telescoped over the drill collars. A reamer on the wash-over pipe frees the drill bit and collars, and during the entire reaming operation, the drill collars are engaged by the retrieving device. Therefore, when the drill bit is dislodged, the drill collars and bit will be prevented from dropping to the bottom of the well bore. Subsequently, the wash-over string, with the drill bit and collars attached, may be removed from the well bore.

In the event the drill bit and collars cannot be removed, or it is not desired to remove them, the drill collars may be gently lowered to rest on the bottom of the well bore and the retrieving apparatus may be sepa-

rated by circulating fluid or drilling mud pressure. The wash-over string may then be removed from the well bore; leaving the drill collars, bit, and a portion of the retrieving apparatus in the bottom of the well bore. At a later time, the drill collars and bit may be recovered from the bottom of the well bore by other suitable tools.

An important object of this invention is to ream around lodged drill collars in a well bore while simultaneously holding the drill collars from downward movement.

Another object of this invention is to provide means for reaming out key-seats lodging drill collars in a well bore and preventing downward movement of the drill collars when they become dislodged.

Another object of this invention is to provide a mechanism for dislodging and recovering lodged drill collars in one operation of running tools in the well bore.

A further object of this invention is to provide a drill collar retrieving mechanism in a wash-over pipe which may be disconnected by hydraulic pressure.

Another object of this invention is to provide a drill collar retriever apparatus in a wash-over pipe which may be disengaged without mechanically lowering disconnecting tools in an oil well bore.

Other objects and advantages of the invention will be evident from the following detailed description, read in conjunction with the accompanying drawings, which illustrate my invention.

In the drawings:

30 Figure 1 is a vertical sectional view of the upper portion of my novel drill collar retrieving apparatus installed in a wash-over pipe.

Figure 2 is a continuation of Fig. 1 illustrating a lower portion of the drill collar retrieving apparatus.

35 Figure 3 is a continuation of Fig. 2 illustrating a still lower portion of the retrieving apparatus.

Figure 4 is a continuation of Fig. 3 showing the bottom portion of the retrieving apparatus engaged with a drill collar.

40 Figure 5 is a vertical sectional view, partially in elevation, similar to Fig. 3 illustrating the initial step of separating the retrieving apparatus.

Figure 6 is another vertical sectional view illustrating the complete separation of the retrieving apparatus.

45 Referring to the drawings in detail, and particularly Figs. 1 to 4, reference character 1 designates a string of wash-over pipe having a tubular reamer 2 (Fig. 4) on the lower end thereof. The wash-over pipe 1 is suspended on the lower end of a string of drill pipe (not shown) which extends to the surface of the well bore (not shown). A slip joint (not shown), preferably of the type shown in my co-pending application Serial No. 390,994, filed November 9, 1953, now Patent No. 2,851,252, should be interposed between the drill pipe 50 and wash-over pipe 1 to permit upward movement of the drill pipe independent of the wash-over pipe 1. Reference character 3 (Fig. 4) designates a drill collar lodged in the well bore and which the reamer 2 is to dislodge when utilizing the present invention.

60 A novel drill collar retrieving mechanism, generally indicated at 4 and shown extending through Figs. 1 to 4, is inserted in the wash-over pipe 1 shortly above the reamer 2. The retrieving mechanism 4 comprises, in the main, a tubular mandrel, generally indicated at 5 and extending from the upper end through the major portion of the mechanism; a wash-over gripping or supporting mechanism (Figs. 2 and 3), generally indicated at 6, for the purpose of slidably supporting the mandrel 5, and a drill collar engaging portion (Figs. 3 and 4), generally indicated at 7, at the lower end of the mechanism for engaging the drill collar 3.

The mandrel 5 is concentrically disposed in the wash-

over pipe 1 and is constructed in several sections. The upper section 8 (Fig. 1) is provided with an enlarged head portion 9 having a downwardly and inwardly tapered bore 10 therethrough. A plurality of transverse apertures 11 extend through the walls of the section 8 slightly below the head 9, and a downwardly facing circumferential shoulder 12 is provided on the outer periphery of the section 8 below the apertures 11.

A tubular shaped orifice housing section 13 is threadedly secured to the lower end of the upper section 8 by a connector member 14. An upwardly extending circumferential flange 15 is formed on the upper end of the connecting member 14 to receive and support a packing unit 16. The flange 15 retains the packing unit 16 in tight contact with the outer periphery of the member 8 and against the shoulder 12. The packing unit 16 provides a fluid seal between the mandrel section 8 and the inner periphery of the wash-over pipe 1 to prevent a downward flow of fluid around the mandrel 5 at this point, as will be more fully hereinafter set forth.

The orifice housing section 13 extends downwardly from the section 8 and is threadedly secured at its lower end to another connecting member or collar 17. A tubular insert 18 is threaded into the collar 17 immediately below the housing section 13 and is retained in the collar 17 by the section 13. The insert 18 extends upwardly in the housing 13, and the inner surface thereof is tapered downwardly and inwardly at the upper end to form a seat 19. An orifice unit 20 is adapted to rest on the seat 19 and assist in the actuation of the mandrel 5. However, the orifice unit 20 is utilized only after the drill collar 3 has been engaged and dislodged, and is not present in the housing 13 at the beginning of the retrieving operation. Therefore, the detailed description of the unit 20, and a companion unit 21, will be deferred to a more appropriate place.

The collar 17 forms a threaded connection between the orifice housing section 13 and a lower tubular section 22 (Figs. 1 and 2) of the mandrel 5. In addition, the collar 17 is externally threaded near its lower end 23 to receive a sleeve or spring guide 24. The spring guide 24 depends from the collar 17 around the mandrel section 22 and has a plurality of transverse apertures 25 in the medial portion thereof for discharging circulating fluid, as will be hereinafter set forth. A helical spring 26 surrounds the mandrel section 22 inwardly of the spring guide 24 and is anchored at its upper end to an adjusting nut 27 threadedly secured to the section 22 immediately below the collar 17.

In the normal operating position of the spring 26, its lower end is substantially even with the lower end of the spring guide 24. A plurality of circumferentially spaced vertical slots 28 are provided in the lower end of the mandrel section 22 immediately above the threaded connection of the section 22 with a still lower tubular mandrel section 29. The section 29 extends concentrically through the supporting mechanism 6.

The supporting mechanism 6 comprises a tubular housing 30 having an inner diameter slightly larger than the outer diameter of the mandrel section 29, thereby providing a sliding fit between these two elements. An extension 31 is threadedly secured to the upper end of the housing 30 and extends upwardly around the mandrel sections 29 and 22. The upper end of the extension 31 provides an anchor for the lower end of the spring 26. The spring 26 has sufficient strength to support the mandrel 5 in the gripping mechanism 6 and continually urges the mandrel 5 in an upward direction.

A plurality of circumferentially spaced vertical slots 32 are provided in the extension 31 opposite the slots 28 in the mandrel section 22. The slots 32 are of greater length than the slots 28, and in cooperation with the slots 28, provide passageways for circulating fluid from the mandrel 5 into the annulus 33 between the extension 31 and the wash-over pipe 1.

The lower end of the extension 31 forms a downwardly facing circumferential shoulder 34 to prevent upward movement of a slip shoe or head 35. The slip shoe 35 surrounds the housing 30 and is keyed thereto by a key 36 to prevent rotation of the shoe 35 on housing 30. Downward movement of the shoe 35 is prevented by the key 36. A plurality of downwardly and inwardly tapered surfaces 37 are arranged in circumferentially spaced relation on the outer periphery of the shoe 35 to receive serrated slips 38. It will be apparent that the slips 38 will engage the wash-over pipe 1 upon downward movement of the shoe 35 and will be disengaged from the wash-over pipe 1 upon upward movement.

Links 39 interconnect the slips 38 with a dog cage 40 through pin type connections 41 at each end of the links 39. The dog cage 40 is tubular in construction and is secured to the outer periphery of the housing 30 by a key 42. The key 42 is loosely disposed in cooperating slots 43 formed in the housing 30 and dog cage 40 to provide a limited vertical movement of the dog cage 40. A plurality of vertical slots 44 are provided in the outer periphery of the dog cage 40 to receive dog members 45. The dogs 45 are radially movable to frictionally engage the wash-over pipe 1 and are constantly urged in an outward direction by small helical springs 46. Transverse pins 47 are secured in the dog cage 40 at each end of each slot 44 and extend through slots 48 in the opposite ends of the dogs 45 to limit the outward movement of the dogs 45.

The housing 30 extends downwardly below the dog cage 40 and has a helical spring 49 thereon resting on a circumferential shoulder 50 on the housing. The spring 49 supports the dog cage 40 and assists in actuation of the slips 38, as will be hereinafter set forth. Referring to Fig. 3, it will be noted that a counter-bore 51 is formed in the lower portion of the housing 30 and contains an expander head 52. The expander head 52 is threadedly secured to the lower end 53 of the mandrel section 29 and is loosely disposed in the counter-bore 51. A shoulder 54 is formed on the lower end 53 of the mandrel section 29 and is of greater diameter than the bore of the housing 30. Thus, the shoulder 54 will contact the upper end of the counter-bore 51 of housing 30 and limit the upward movement of the expander head 52. The expander head 52 has an upper portion 52a of smallest external diameter, and an intermediate portion 55 of external diameter larger than the smallest portion 52a, and a lower portion 56 of greatest external diameter engageable with dogs 57 inserted in vertical slots 58 of the housing 30. The largest portion 56 of the expander head 52 engages the dogs 57 to maintain them in expanded position for locking the sleeve 59 of the drill collar engaging means 7 to the housing 30. The dogs 57 are circumferentially spaced around the housing 30 opposite the counter-bore 51, and are adapted to move radially in the slots 58 to engage in circumferentially spaced recesses (not shown) provided in the sleeve 59 of the drill collar engaging mechanism 7 as will be hereinafter set forth. An inwardly extending shoulder 60 is formed on the upper end of each dog 57 to cooperate with the expander head 52.

Additional vertical slots 61 are formed in the housing 30 below the dogs 57 to receive shear pins 62 extending inwardly from the sleeve 59. The shear pins 62 assist in supporting the drill collar engaging mechanism 7, particularly in the event the dogs 57 are not operating, to prevent inadvertent release of the mechanism 7. A bearing retaining ring 63 is secured in the sleeve 59 below the lower end 64 of the housing 30 by a plurality of bolts 65. The bearing retaining ring 63 rests upon a thrust bearing unit 66, which in turn is disposed on the upper end 67 of another tubular section 68 of the drill collar engaging mechanism 7.

The sleeve 59 is threadedly secured to the upper end 75 67 of the section 68 and the threaded engagement is

retained by a lock screw 69. A tubular insert 70 is threadedly secured in the upper end of the sleeve 59 above the dogs 57. The insert 70 extends downwardly in the sleeve 59 and prevents upward movement of a rubber bumper ring 71 and a metal shock ring 72 disposed in the sleeve 59. The rings 71 and 72 are utilized to assist in the retraction of the dogs 57, as will be hereinafter set forth, and the lower end 73 of the shock ring 72 is tapered upwardly and inwardly to facilitate actuation of the dogs 57. A circumferential shoulder 74 is formed on the inner periphery of the sleeve 59 to prevent downward movement of the rings 71 and 72 relative to the sleeve 59.

Referring to Fig. 4, it will be noted that the tubular section 68 of the drill collar engaging mechanism 7 screws into a lower tubular member 75 which extends on down in the wash-over pipe 1 and terminates in a head or slip shoe 76. A sleeve 77 is threadedly secured around the member 75 adjacent the upper end thereof and extends downwardly around the member 75 to form a guide for a helical spring 78. The spring 78 surrounds the member 75 and is anchored at its upper end to a downwardly facing shoulder 79 on the member 75. The lower end of the spring 78 rests on a floating ring 80 which is also disposed around the member 75 within the spring guide 77. A circumferential recess 81 is formed in the inner periphery of the ring 80 to receive the upper ends of a plurality of links 82. The outer periphery of the member 75 is cut away at 83 opposite the ring 80 to assure free vertical movement of the ring 80 and links 82.

Each link 82 is pinned to the upper end of a threaded slip 84. The slips 84 are disposed in circumferentially spaced vertical slots 85 formed in the outer periphery of the head 76. Bolts 86 are secured in the lower portion of each slot 85, thereby providing stops to limit the downward movement of the slips 84. The slots 85 are tapered downwardly and outwardly to force the slips 84 into engagement with the threaded box 87 of the drill collar 3 as will be hereinafter set forth.

Operation

To recover the lodged drill collar 3, the wash-over pipe 1, with the reamer 2 attached to the lower end thereof and the retrieving apparatus 4 disposed above the reamer 2, is lowered in the well bore. When the apparatus 4 is inserted in the wash-over pipe 1, the friction dogs 45 (Fig. 2) engage the inner periphery of the wash-over pipe 1 and support the entire apparatus 4. Furthermore, the spring 26 (Fig. 2) will exert an upward force on the mandrel 5 to retain the expander head 52 in its uppermost position as shown in Fig. 3 with the flange 54 in contact with the upper end of the counter-bore 51. Thus, the largest portion 56 of the expander head 52 will be in contact with the inner periphery of the dogs 57 to retain them in engagement with the sleeve 59 and support the drill collar engaging mechanism 7. As previously noted, the orifice units 20 and 21 are not present in the orifice housing section 13 of the mandrel 5 at this time.

The entire wash-over string, comprising the wash-over pipe 1 and drill pipe interconnected by a slip joint, are lowered and rotated in the well bore to provide a reaming action of the reamer 2 and remove all key-seats existing in the well bore. Simultaneously, drilling mud, or circulating fluid, is pumped downwardly through the wash-over string to remove cuttings produced by the reamer 2 and wash the cuttings upwardly in the annulus between the wash-over string and well bore. The fluid enters the mandrel 5 through the tapered bore 10 (Fig. 1). A portion of the fluid passes outwardly through the apertures 11 and downwardly around the head 9 to force the packing unit 16 outwardly and form a seal with the wash-over pipe 1. The remainder of the fluid flows on down through the sections 8, 13 and 22 of the mandrel 5. It will be noted that the bore 29a of the mandrel section 29 is smaller than the bore of the section 22, therefore a portion of the fluid is diverted through the slots

28 and 32 into the annulus 33. The diverted fluid flows downwardly in the annulus 33 around the supporting mechanism 6 and drill collar engaging mechanism 7 to flush out the reamer 2. The remainder of the fluid flows on down through section 29, expander head 52, section 68 and member 75 into the drill collar 3 to assist in dislodging the drill collar 3.

As the wash-over pipe 1 and reamer 2 are telescoped over the drill collar 3, the head 76 and slips 84 enter the box 87 of the drill collar 3. The rotative motion of the entire apparatus 4, in combination with downward force of the spring 78, threads the slips 84 in the box 87. When the slips 84 engage the box 87, the entire apparatus 4 stops moving in a downward direction, but the wash-over pipe 1 continues moving in a downward direction and rotates to continue the reaming action around the drill collar 3. It will then be noted that the wash-over pipe 1 will exert a downward force on the friction dogs 45 to assure a disengagement of the slips 38.

The rotative and downward movement of the wash-over string is continued until the drill collar 3 is dislodged, whereupon the drill collar 3 will tend to fall to the bottom of the well bore. The downward force caused by the initial downward movement of the drill collar 3 is transmitted through the slips 84, head 76, member 75, section 68, sleeve 59, dogs 57 and housing 30 to the slip shoe 35. Since the friction dogs 45 will tend to remain stationary within the wash-over pipe 1, and are urged upwardly by the spring 49, the shoe 35 will move downward through the slips 38 and expand them into engagement with the wash-over pipe 1. When the slips 38 become engaged, the drill collar 3 is effectively secured to the wash-over pipe 1 and will be prevented from further falling.

The entire wash-over string, with the drill collar 3 attached, may then be removed from the well bore. However, if it is not deemed expedient to remove the drill collar 3 with the apparatus 4, the wash-over string may be lowered to place the drill collar 3 on the bottom of the well bore; whereupon the retriever 4 may be separated to permit separate removal of the wash-over string.

Separation of the retriever 4 is accomplished hydraulically through use of the orifice unit 20 (Fig. 1). The unit 20 comprises a tubular plug 91 having a lower tapered end 92 constructed to rest upon the seat 19. A sealing ring 93 is placed on the tapered portion 92 to provide a seal with the seat 19 and prohibit flow of circulating fluid around the plug 91. The inner bore of the plug 91 is partially threaded to receive a threaded bushing 94 and a tubular extension 95. A frangible solid disc 96 may be secured in the plug 91 by the bushing 94, however, the disc 96 is not ordinarily used, as will be shown hereinafter. The upper inner end of the extension 95 is tapered inwardly and downwardly to form a seat 97 for the orifice unit 21. The remaining length of the inner bore of the insert 95 is similarly tapered, but to a much lesser extent, to receive an orifice plate 98. It will be apparent that the orifice plate 98 is wedged into the extension 95, and that the plate 98 will restrict the flow of circulating fluid through the mandrel 5.

When it is desired to separate the retriever 4, the orifice unit 20 is pumped down through the wash-over string by the circulating fluid and comes to rest on the seat 19. Continued pumping of the circulating fluid causes an increase of fluid pressure above the orifice plate 98 due to its decreased opening. The pressure on the mandrel 5 is increased until enough force is built up to overcome the action of the spring 26; whereupon the mandrel 5 moves downwardly through the supporting mechanism 6. As shown in Fig. 5, the expander head 52 is therefore moved downwardly to move the portion 55 below the shoulders 60 of the dogs 57. The dogs 57 are then free to move inwardly out of engagement with the sleeve 59 and free the drill collar engaging mechanism 7.

After the expander head 52 is moved down, an upward

pull is exerted on the wash-over string. The dogs 57, being released, will exert no appreciable force on the sleeve 59, therefore the housing 30 will move upwardly through the sleeve 59. Furthermore, as the housing 30 is being moved up through the sleeve 59, the tapered end 73 of the shock ring 72 will contact the dogs 57 and move them inwardly into the counter-bore 51 in contact with the head 52. The force required to raise the wash-over string will be sufficient to shear off the pins 62 (the only remaining attachment between the holding mechanism 6 and drill collar engaging mechanism 7) and free the housing 30 from the sleeve 59 as shown in Fig. 6. The wash-over string is then free for removal from the well bore; leaving the drill collar engaging mechanism 7 attached to the drill collar 3 at the bottom of the well bore. Other recovery tools may then be inserted in the well bore for recovering the drill collar 3.

The circulating fluid will harden around the reamer 2 at times and restrict the flow through the retriever 4. When such a condition occurs, it may be impossible, or at least impracticable, to build up enough pressure on the mandrel 5 to compress the spring 26 by using only the orifice plate 98. In this event, the frangible disc 96 may be secured in the plug 91. The disc 96 will prohibit the flow of fluid through the mandrel 5 until an appreciable pressure is built up above the orifice unit 20 to compress the spring 26; whereupon the disc 96 will rupture and permit further flow of fluid through the retriever 4 to prevent hardening of the fluid therein.

A similar orifice unit 21, having an orifice plate 99 and frangible disc 100 therein, may be pumped down on the seat 97 if additional restriction in the mandrel 5 (and hence increased pressure for compressing the spring 26) is desired. The orifice plate 99 is provided with a smaller orifice than the plate 98 to further reduce the flow of fluid through the mandrel 5.

From the foregoing, it is apparent that the present invention provides a novel drill collar retrieving apparatus for simultaneously holding and dislodging drill collars stuck in a well bore, whereby the drill collars will not fail and be damaged. The drill collars may be dislodged and removed with one trip of tools in the well bore. Furthermore, the retrieving apparatus may be disconnected or separated from the drill collars by hydraulic pressure and without mechanically lowering tools in the well bore.

Changes may be made in the combination and arrangement of parts as heretofore set forth in the specification and shown in the drawings, it being understood that any modification in the precise embodiment of the invention may be made within the scope of the following claims without departing from the spirit of the invention.

I claim:

1. An apparatus for retrieving one or more drill collars lodged in a well bore, comprising a wash-over pipe string of a size to enter the well bore and telescope over a drill collar, a reamer on the lower end of the wash-over pipe string to dislodge the drill collar, a tubular housing in the wash-over pipe string, dogs reciprocally carried by the housing and frictionally engaging the wash-over pipe string, a slip shoe on the housing, slips on the slip shoe connected to the dogs, mandrel means extending through the housing and slidably supported therein, said mandrel means being responsive to fluid pressure for movement in one direction through the housing, spring means provided in the housing for urging the mandrel in an upward direction in relation to the housing and supporting the mandrel in an upper position, and drill collar engaging means releasably secured to the housing, a second set of dog means carried by the housing means, and expander head means provided on the mandrel for actuation of the second dog means for securing the drill collar engaging means to the housing in one position of the mandrel means and separated from the housing in a second position of the mandrel means.

2. An apparatus for retrieving one or more drill collars

lodged in a well bore, comprising a wash-over pipe string of a size to enter the well bore and telescope over a drill collar, a reamer on the lower end of the wash-over pipe string to dislodge the drill collar, a tubular housing in the lower portion of the wash-over pipe string, wash-over pipe gripping means mounted on the tubular housing, tubular mandrel means extending through the housing and slidably therein in one direction in response to fluid pressures, spring means on the housing for urging the mandrel means upward relative to the housing and supporting the mandrel means in its upper position, drill collar engaging means, dogs carried by the housing for securing the drill collar engaging means to the housing, expander means provided on the lower end of the mandrel whereby in the upper position of the mandrel said expander means locks said last mentioned dogs in an expanded position for locking the drill collar engaging means to the tubular housing, said last mentioned dogs being operable by the tubular housing for releasing the drill collar engaging means upon downward movement of the expander means, and means for applying fluid pressure on the mandrel means to move the mandrel means in a downward direction through the housing and releasing the drill collar engaging means.

3. A drill collar retrieving apparatus for use in a wash-over pipe having fluid flowing downwardly therethrough, comprising a tubular housing in the wash-over pipe, dogs reciprocally carried by the housing and frictionally engaging the wash-over pipe, a slip shoe on the housing, slips on the slip shoe operable by the dogs to engage the wash-over pipe upon downward movement of the housing in the wash-over pipe, tubular mandrel means extending through the housing and reciprocal therein in response to opposing mechanical pressure and fluid pressure, spring means in the housing yieldably supporting the mandrel means, an expander head on the mandrel means, drill collar engaging means, a second set of dogs on the housing for releasably securing the drill collar engaging means to the housing, said second set of dogs being operable by the expander head for radially expanding the second dogs for securing the drill collar means to the housing, and means for varying the fluid pressure applied to the mandrel means, whereby the expander head may be moved downwardly to permit movement of the second set of dogs in order to release the drill collar engaging means.

4. A drill collar retrieving apparatus for use in a wash-over pipe having fluid flowing downwardly therethrough, comprising a tubular housing in the wash-over pipe, dogs reciprocally carried by the housing and frictionally engaging the wash-over pipe, a slip shoe on the housing, slips on the slip shoe operable by the dogs to engage the wash-over pipe upon downward movement of the housing in the wash-over pipe, tubular mandrel means extending through the housing and reciprocal therein in response to opposing mechanical and fluid pressure, spring means on the housing urging the mandrel means upwardly with respect to the housing and yieldably supporting the mandrel means in its upper position, an expander head on the mandrel means, drill collar engaging means, a second set of dogs on the housing for releasably securing the drill collar engaging means to the housing, said second set of dogs being operable by the expander head in the upper position of the mandrel means for locking the dogs in an expanded position for locking the drill collar engaging means to the housing, a packing unit around the mandrel in contact with the wash-over pipe, an orifice unit insertable in the tubular mandrel means adjacent the packing unit for reducing the inner diameter of the mandrel means and increasing the fluid pressure on the mandrel means, whereby the expander head may be moved downwardly to permit movement of the second set of dogs in order to release the drill collar engaging means.

5. An apparatus for retrieving one or more drill col-

lars lodged in a well bore, comprising a wash-over pipe string of a size to enter the well bore and telescope over a drill collar, a reamer on the lower end of the wash-over pipe string to dislodge the drill collar, a holding assembly comprising a wash-over pipe gripping and drill collar supporting means in the lower portion of the wash-over pipe string, mandrel means extending through the wash-over pipe supported by said supporting means and movable relative thereto, a longitudinal bore in the mandrel having a portion thereof restricted, said mandrel responsive to flow of fluid under pressure to move the mandrel in one direction relative to the holding assembly, spring means provided in the holding assembly urging the mandrel in a direction opposite to said first mentioned direction, drill collar engaging means releasably securable to the supporting means, dog means carried by the supporting means, and expander means provided in the mandrel means for actuating the dog means for securing the drill collar engaging means to the supporting means when said mandrel means is moved in said opposite direction, said expander means moved downwardly by the mandrel means for releasing the drill collar engaging means from the supporting means upon movement of the mandrel means in said first mentioned direction.

6. An apparatus for retrieving one or more drill collars lodged in a well bore, comprising a wash-over pipe string of a size to enter the well bore and telescope over the drill collar, a reamer on the lower end of the wash-over pipe to dislodge the drill collar, a holding assembly comprising a wash-over pipe gripping and drill collar supporting means in the lower portion of the wash-over pipe string, said gripping means comprising a plurality of friction dogs engaging the wash-over pipe string, a slip shoe connected to the friction dogs, a plurality of slips on the slip shoe for engaging the wash-over pipe string upon movement of the slip shoe downwardly therein, mandrel means extending through the wash-over pipe supported by said supporting means and movable relative thereto, a longitudinal bore in the mandrel means having a portion thereof restricted, said mandrel means being responsive to flow of fluid under pressure to move the mandrel in one direction relative to the holding assembly, spring means provided in the holding assembly urging the mandrel in a direction opposite to said first mentioned direction, drill collar engaging means releasably securable to the supporting means, dog means carried by the supporting means, and expander means provided in the mandrel means for actuating the dog means for securing the drill collar engaging means to the supporting means when said mandrel means is moved in said opposite direction, said expander means moved downwardly by the mandrel means for releasing

the drill collar engaging means from the supporting means upon movement of the mandrel means in the said first mentioned direction.

7. An apparatus for retrieving one or more drill collars lodged in a well bore, comprising a wash-over pipe string of a size to enter the well bore and telescope over a drill collar, a reamer on the lower end of the wash-over pipe string to dislodge the drill collar, a holding assembly comprising a wash-over pipe gripping and drill collar supporting means in the lower portion of the wash-over pipe string, mandrel means extending through the wash-over pipe supported by said supporting means and movable relative thereto, a longitudinal bore in the mandrel having a portion thereof restricted, said mandrel responsive to flow of fluid under pressure to move the mandrel in one direction relative to the holding assembly, spring means provided in the holding assembly urging the mandrel in a direction opposite to said first mentioned direction, drill collar engaging means carried by the supporting means, expander means provided on the mandrel means, and means carried by the supporting means and actuated by the expander means upon movement of the mandrel means in said opposite direction for releasably securing the drill collar engaging means to the supporting means.
8. An apparatus for retrieving one or more drill collars lodged in a well bore, comprising a wash-over pipe string, a reamer on the lower end of the wash-over pipe string to dislodge the drill collar, a holding assembly comprising a wash-over pipe gripping and drill collar supporting means in the wash-over pipe string, a mandrel extending through the wash-over pipe and supported by the supporting means and movable relative thereto, a longitudinal bore in the mandrel having a portion thereof restricted, said mandrel being responsive to flow of fluid under pressure to move the mandrel in one direction relative to the holding assembly, spring means provided in the holding assembly urging the mandrel in a direction opposite said first mentioned direction, drill collar engaging means carried by the supporting means, expander means provided on the mandrel, and dogs carried by the supporting means and actuated by the expander means upon movement by the mandrel for alternately securing the drill collar engaging means to the supporting means and releasing the drill collar engaging means from the supporting means.
